ATTORNEY

UNITED STATES PATENT OFFICE.

SAMUEL J. MIROSAV, OF DALLAS, TEXAS.

SAVINGS BANK.

Application filed November 20, 1926. Serial No. 149,778.

This invention relates to savings banks, and it has particular reference to a savings bank of such construction as to enable it to be disposed and locked within a wall member and it has for its principal object to provide a savings bank capable of being conjointly associated with an article of utility, as for example, a shoe shining box, and by which the incentive to save coins is encouraged especially in children.

Further objects and advantages of the invention reside in its novel construction and method of assembly, which will become apparent as the description proceeds, taken in connection with the accompanying drawings, wherein:

Figure 1 represents a side elevational view of a portable shoe shining box with the invention attached.

Figure 2 is a similar view showing the shoe support removed to operative position.

Figure 3 is an end view.

Figure 4 is a cross-sectional view on lines 4-4 of Figure 1.

Figure 5 is a view on lines 5-5 of Figure 4.

Figure 6 is a detail view in perspective of the savings bank support, and

Figure 7 is an underside view of Figure 5, with portions in section.

With the foregoing in view, particular attention is directed to Figure 1, showing preferably a metal box 1, used as a container for the shoe shining equipment illustrated in Figure 2. A hinged cover 2 is so disposed as to swing from the position shown in Figure 1 to the position shown in Figure 2 whereby, in the latter position, a foot support 3 affixed thereto is moved to a position to conveniently support the foot in polishing the shoe. The handle 4, by which the box 1 is conveyed from place to place is countersunk as shown in Figure 4 particularly, as so not to interfere with the proper positioning of the cover 2.

When its purpose has been served, the support is moved back to the position as in Figure 1, interiorly of the box 1 and the latch 5 is thrown to retain the cover 2 in place.

Referring now particularly to the small bank or coin receiver affiliated with the box and embodying the invention; it will be noted that a recess is made in the end of the box of sufficient depth as to partially re-

ceive the coin receiver 6. This recess may be either made by depressing the metal or forming a metal shell 7, such as shown in Figure 7 and riveting the same in place. Reference to Figure 5 will disclose the means and the manner in which the container 6 is retained within the recess. This means consists of a member 8 such as illustrated in detail in Figure 6, which is formed to jointly support the container 6 and retain the bottom 9 in the container, by being passed through apertures made therein. See Figure 5 for example. A small padlock 10 is applied to the protruding end of the member 8 to prevent ready removal of the container 6 and its contents.

The top of the container 6 has a countersunk covering in which is made a coin slot 11. Countersinking this cover affords an annular flange at the top of the container, behind which a key 12 is turned, interiorly of the box 1, to constrain the top of the bank 6 from outward displacement.

In order to remove the contents from the bank 6, it is necessary to unlock the padlock 10, raise the cover 2, pull out the member 8, and turn the key 12 to release the top of the bank. When removed from the recess, the bottom 9 will fall from its position shown in Figure 5.

The device described affords a convenient and compact container for the shoe shining equipment in the home, and the added advantage of having an accessible support for the foot while brushing the shoe, the invention affording a receiver for the coin which otherwise would be spent elsewhere, and especially encouraging children to take an interest in saving the coins so earned.

What is claimed is:

1. The combination with a wall member of a savings bank disposed in a recess in said wall member; a loose bottom in said bank; means for jointly retaining said bank and bottom comprising a member arranged to be passed through apertures in the walls of said bank and bottom and engaging the inner side of said wall member, a locking means for said member, and a key pivoted interiorly of said wall member to engage said bank to constrain the top of the latter from outward displacement.

2. The combination with a wall member of a savings bank arranged to reside within a recess in said wall member; a combined supporting and locking means therefor com-

prising a member arranged to pass jointly through the walls and bottom of said bank, and engaging the inner side of the wall member and means pivoted interiorly of said wall member to engage and hold the top of said bank against outward movement from said recess.

3. The combination with a wall member of a savings bank arranged for organization therewith comprising a coin receiving receptacle partially receivable within a recess in one end of said wall member; a member having one end turned downward to engage the inner side of the wall member and passing jointly through the walls of said coin receptacle and its bottom; a padlock carried by the protruding end of said member and

means pivoted interiorly of said wall member to engage and hold the top of said receptacle in the recess.

4. The combination with a wall member of a coin receptacle removably mounted in a recess in said wall member; means for so supporting said receptacle; said means comprising a member insertable jointly through apertures in the walls and bottom of said receptacle to also hold the bottom intact, and engaging the inner side of said wall member, a locking means for said member, and means arranged near the top of said receptacle to prevent outward displacement of that part of said receptacle from the recess.

In testimony whereof I affix my signature.

SAMUEL J. MIROSAV.
